(57) **CLAIM**

The ornamental design for a remote control page turner set, as shown and described.

DESCRIPTION

FIG. 1 is a first perspective view of a remote control page turner set showing a new design;

FIG. 2 is another perspective view thereof;

FIG. 3 is a front elevational view of a remote control of a remote control page turner set of FIG. 1, showing my new design, shown separately for ease of illustration;

FIG. 4 is a rear elevational view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a front elevational view of a page turner of the remote control page turner set of FIG. 1, shown separately for ease of illustration;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines in the drawings illustrate the portions of the remote control page turner set, which form no part of the claimed design.

1 Claim, 14 Drawing Sheets
